UNITED STATES PATENT OFFICE.

HENRY X. WRIGHT, OF MEMPHIS, TENNESSEE, ASSIGNOR OF ONE-HALF TO
JAMES D. WRIGHT, OF BERGEN, NEW JERSEY.

IMPROVEMENT IN LIGHTING ATTACHMENTS FOR CLOCKS.

Specification forming part of Letters Patent No. **149,366**, dated April 7, 1874; application filed
June 26, 1873.

To all whom it may concern:

Be it known that I, HENRY X. WRIGHT, of the city of Memphis, county of Shelby, State of Tennessee, have invented certain Improvements in Lighting Attachments for Clocks, of which the following is a specification:

The object of my invention is to provide for lighting a candle at any time in the night which may be desired.

My invention consists in certain details of construction first described, and afterward pointed out in the claim.

In order more fully to describe my invention, I refer to the accompanying drawing forming a part of this specification.

Figure I is a front view of an alarm-clock embodying my invention. Fig. II is a side view of the same.

A candle-holder, I, is attached to one side of the casing A of an alarm-clock, and projects in front of the same to show the time as soon as the candle is lighted. Near the place where the candle-holder is fastened a vertical spring, K, is placed, having on its upper end a match-holder, N. Near the top of the casing a piece of sand-paper is fastened on a line with the match-holder. Under the sand-paper holder is inserted a pin, R, with an arm, S, against which the spring K is placed, when the lighting attachment is set for operation. A horizontal rod, G, passes through the side of

the casing, having on its inner end a shoulder, h, which rests against a pin, f, in the disk e on the winding-post d of the alarm. The rod G serves as a trip-shaft to the spring K, and is drawn out by the hand to hold the spring in position ready for lighting the match. When the alarm strikes, the winding-post of the alarm revolves, drawing in the trip-shaft, releasing the spring, which ignites the match and communicates the flame to the candle-wick. To prevent the spring from being thrown beyond the candle, a stop, n, is placed on the side of the casing near the pivot of said spring. A guide, T, to direct the forward movement of the spring is placed above and to the rear of the pin and arm above mentioned, and against which the spring K rests when placed in position for operation.

Having thus fully described my invention, I claim—

The elastic wire arm K having coiled match-holder N, in combination with the trip-arm G, operated by disk e, carrying stud f, all arranged in connection with a clock for lighting a lamp or candle at a determined time, substantially as set forth.

HENRY X. WRIGHT.
